UNITED STATES PATENT OFFICE.

JAMES JONES, JR., OF NEW YORK, N. Y.

BURGLAR-ALARM.

1,115,830.

Specification of Letters Patent.

Patented Nov. 3, 1914.

Application filed January 13, 1912. Serial No. 671,064.

To all whom it may concern:

Be it known that I, JAMES JONES, Jr., of the city of New York, in the county of Kings and State of New York, have invented certain new and useful Improvements in Burglar-Alarms; and I do hereby declare the following to be a full, clear, and exact description of the invention, such as will enable others skilled in the art to which it appertains to make and use the same.

My object is to provide a simple and inexpensive device composed of but few parts and hence not likely to get out of order, and which will be positive in its action and not likely to be operated accidentally.

In the drawing Figure 1 is an elevation of an alarm constructed in accordance with my invention. Fig. 2 is an end view showing the position of the parts when the door is open. Fig. 3 is a similar view with the door closed. Fig. 4 shows the alarm sounded. Figs. 5, 6 and 7 show top plan views of the parts in the positions illustrated in Figs. 2, 3, and 4, respectively. Fig. 8 is a diagram 25 of the electric circuit.

Referring to the drawing, 1 designates a box adapted to be secured to a door at the top of the latter and equipped with hooks 2 by which it may be secured. This box contains a battery and carries a suitable signal, as a bell.

At 3 I have shown the box provided with a presser foot which is normally held advanced by the tension of a spring 4. In its advanced position the presser foot extends beyond the box and is adapted to contact with a door frame when the door is closed and thus retract the presser foot against the tension of the spring.

At 5 I have shown a suitable bearing plate for the presser foot and the latter is formed at its inner end with a reduced portion 6 thus providing a shoulder 7 and an extremity 8.

The circuit closing element is shown at 10. This preferably consists of a weighted sleeve freely movable on a vertical rod 12 supported by the box 1. This rod, preferably at its top, is in circuit with the battery. (See Fig. 8.) A plate 13 is shown attached to the front of the box and this plate is also in circuit with the battery and has a free end 14 normally lying adjacent the rod 12.

I have shown the circuit closer 10 formed with a laterally projecting flange 15 and the top of the box with a keeper plate 16 having

vertical flanges 17 and 18. Flange 18 extends diagonally across the top of the box at the corner adjacent the presser foot 3 so that when the flange 15 is placed outside of the flange 18 its extremity will intersect the path of movement of the presser foot. When the alarm is not in use or its use is not desired the flange 15 lies between the flanges 17 and 18, as in dotted lines, Fig. 5. When the circuit closer is set for use and is tripped by the presser foot it falls by gravity to the position shown in Figs. 4 and 8, thus closing the circuit by contact with extremity 14 of plate 13 and causes the alarm to sound, the alarm continuing until the circuit is broken.

To set the alarm the flange 15 is placed across the corner of the box outside of flange 18 of the keeper plate. (See Fig. 5.) The occupant of the room or apartment equipped with the alarm may set it before going out so that the alarm will be operated if the door should be opened in his absence and still permit him to leave without causing the alarm to sound. To do this the door may be either open or closed when the circuit closer 10 is placed with its flange 15 extending in the path of the presser foot. If the door is open, as in Figs. 2 and 5, the flange rests upon the corner of the box and out of contact with the presser foot but in the path of movement of shoulder 7. The occupant of the premises may then pass out of the door and close it. This causes the presser foot to move inward and the shoulder 7 to push the flange 15 off of the box and fall on to the reduced portion 6. (See Figs. 3 and 6.) The next time the door is open the advance of the presser foot will leave the circuit closer without a support and the latter will fall off the edge 8 and close the circuit. (See Figs. 4, 7 and 8.) If, on the other hand, the door be closed when the alarm is set the flange 15 will simply rest upon the top of the shoulder 7 as in dotted lines, Fig. 6, and as the occupant opens the door and passes out the flange 15 will fall from this shoulder on to the top of the box, as in Figs. 2 and 5, and when the occupant closes the door behind him the flange 15 will fall upon the part 6 of the presser foot as in Figs. 3 and 6, as before described.

When the occupant of the premises is within and it is desired that the alarm be sounded at the first opening of the door the

latter is closed and then the circuit closer is placed so that it is supported only by the flange 15 resting upon the extremity 6 of the presser foot. (See Fig. 6.) When thus 5 set the first operation of opening the door results in sounding the alarm.

I claim as my invention:—

1. In an electric alarm for doors and the like, the combination with the box having 10 an electric battery and a suitable signal, and having a guide in electrical connection with said battery, and a contact member also in electrical connection with said battery and lying adjacent said guide, of a gravitating 15 circuit closer freely movable on said guide, means for normally supporting said circuit closer out of engagement with said contact member, and means operated by the opening of the door for removing said supporting 20 means from said circuit closer and allowing it to fall and form a connection between said guide and said contact member.
2. In an electric alarm for doors and the like, the combination with the box having 25 an electric battery and a signal and having a vertically disposed rod secured thereto, said rod being in electrical connection with said battery, and a contact plate having a free end adjacent said rod, of a weighted 30 sleeve movable on said rod, means for supporting said sleeve near the top of said rod, and means operated by the opening of the door for unseating said sleeve and causing it to fall into contact with said plate.
3. In an electric alarm for doors and the like, the combination with the normally 35

open electric circuit having contacts, one of said contacts consisting of a vertically disposed rod, and the other contact being near the lower end of said rod, of a weighted 40 sleeve normally supported near the top of said rod, and means rendered effective by the opening of the door for unseating said sleeve and causing it to fall and establish a connection 45 between said contacts.

4. In an electric alarm for doors and the like, the combination with the box or casing having a normally open circuit and contacts, of a weighted sleeve having a lateral flange movable on one of said contacts, 50 means for normally supporting said flange, of a presser foot rendered effective upon opening the door to remove said supporting means from said flange and cause said sleeve to fall by gravity to connect said contacts. 55

5. In an electric alarm for doors and the like, the combination with the box having a spring actuated presser foot adapted to engage a door frame and be retracted when the door is closed, said box having a normally open electric circuit, of a gravitating element and means for normally supporting the same in position to be unseated by the action of said presser foot to close said contacts. 60

In testimony whereof, I have signed this specification in the presence of two subscribing witnesses.

JAS. JONES, JR.
